UNITED STATES PATENT OFFICE.

JOSEPH W. COLCORD, OF LYNN, MASSACHUSETTS.

BOTTLE-TAP.

SPECIFICATION forming part of Letters Patent No. 280,798, dated July 10, 1883.

Application filed May 1, 1883. (No model.)

To all whom it may concern:

Be it known that I, JOSEPH WEBSTER COLCORD, of Lynn, in the county of Essex, of the Commonwealth of Massachusetts, have invented a new and useful Improvement in Bottle-Taps; and I do hereby declare the same to be described in the following specification and represented in the accompanying drawings, of which—

10 Figure 1 is a side elevation of a bottle with one of my improved taps applied to it. Fig. 2 is a side view, and Fig. 3 a vertical and longitudinal section, of the tap separate from the bottle.

15 This tap is to enable the liquid contents of the bottle to be expelled therefrom through an educt by means of air forced into the bottle. In some respects the tap is analogous to that for effecting the discharge of the liquid contents of a bottle by pressure on the liquid of carbonic-acid gas generated in such contents by fermentation thereof.

The nature of my invention is defined in the claim hereinafter presented.

20 In Fig. 1 of the drawings, A represents a bottle having the tubular corkscrew D of the tap B screwed into and down through the cork C of such bottle, the said tap having a pipe, a, to extend and slide through the tubular corkscrew D down into the bottle nearly to its bottom. The said pipe a has to the upper part of its bore g a stop-cock, E, and a nozzle, F, the latter extending from the stop-cock in manner as represented. The corkscrew D is formed with an air-passage, b, which is entirely distinct from the bore of said corkscrew. This passage is made vertically in the corkscrew alongside of said bore, and runs from the lower end of the corkscrew 25 up into the head B of the same, at which point it is connected with a transverse passage, b', in such head. This head is connected by a suitable coupling with an elastic air-forcing bulb, G, having at one end an induction-valve, 30 c, and at the other an eduction-valve, d. A flexible pipe, e, connects the bulb with the air-passage by means of a proper coupling, f, such as will admit of air passing from the pipe e into such passage.

35 Before applying the tap to a corked bottle

it is customary to insert loosely in the tube a, at its lower end, a metallic point that will easily fall out of the pipe on the passage of it through the cork. Having done this and forced the pipe and point down through the cork until 55 the corkscrew may have reached the said cork, such corkscrew is to be revolved, so as to screw it closely down into and through the cork. The bulb should be next alternately compressed by hand and allowed to expand, 60 whereby air will be forced into the bottle and compressed therein. On opening the stop-cock the elastic force of the compressed air in the bottle will drive the liquid thereof through the pipe a and the stop-cock and nozzle. The 65 said nozzle is a convenient auxiliary to the stop-cock, and may be curved or formed as occasion may require.

By having the pipe a to slide tightly through the corkscrew the tap can be adapted to bottles of different heights, the pipe a, after having been inserted, being pressed down nearly to the bottom of the bottle.

With my invention adapted to a bottle the latter may be kept securely closed when it 75 may not be desirable to extract from it any of its liquid contents, and the liquid may be expelled from it as occasion may require.

I am aware that a bottle-tap has been devised provided with an exterior thread and an 80 interior bore, through which bore passes an eduction-pipe having a cock at its upper end, the said bore being larger than the pipe, and having a tube leading within, so that air may be forced through the bore into the bottle and 85 the contents of the latter up the pipe. In my device the eduction-pipe fits tightly the bore of the tap through which it passes, there being no space whatever around the pipe in the tap. The air is forced into the bottle through a passage which passes down the tap, entirely disconnected from the bore or passage in which the eduction-pipe operates. By having a distinct passage for the air alone, such passage is 90 always kept free and clear, no accumulation 95 from the contents of the bottle can be drawn therein, nor will pieces of the cork become jammed therein in pushing the tap through the cork. As the eduction-pipe tightly fits the bore the entire length of the tap, the con- 100

nection between the two is completely air-sealed; hence the bottle can be filled with compressed air and kept in that condition indefinitely, as there is no danger of the air escaping.

Having described my invention, what I claim is—

A bottle-tap having a main bore and a dis-

tinct air-passage, in combination with an education-pipe passing through and closely fitting to such bore, as set forth.

JOSEPH WEBSTER COLCORD.
